UNITED STATES PATENT OFFICE

104,236

DESIGN FOR A SIGN UNIT OR THE LIKE

Edmund Norwood Bacon, Bloomfield Hills, Mich.,
assignor to W. B. Farrell Associates, Inc.

Application March 18, 1936, Serial No. 61,684

Term of patent 14 years

To all whom it may concern:

Be it known that I, Edmund Norwood Bacon, a citizen of the United States, residing at Bloomfield Hills, in the county of Oakland and State of Michigan, have invented a new, original, and ornamental Design for a Sign Unit or the like, of which the following is a specification, reference being had to the accompanying drawing, forming part thereof.

The letters illustrated in the drawing figures indicate merely the conventional type of letters. The side of the sign unit opposite to that shown in Fig. 1 is the same as the side illustrated in the drawing. The shaded bands in the drawing figures are intended to represent contrasting color.

I claim:

The ornamental design for a sign unit or the like as shown and described.

EDMUND NORWOOD BACON.
